UNITED STATES PATENT OFFICE.

BERNHARDT SCHENK AND JOSEPH SZOKE, OF CHICAGO, ILLINOIS.

POWER PIPE-BENDING MACHINE.

1,277,488.

Specification of Letters Patent. Patented Sept. 3, 1918.

Application filed February 9, 1918. Serial No. 216,190.

To all whom it may concern:

Be it known that we, BERNHARDT SCHENK and JOSEPH SZOKE, citizens of the United States, and residents of Chicago, in the county of Cook and State of Illinois, have jointly invented certain new and useful Improvements in Power Pipe-Bending Machines; and we do hereby declare that the following description of our said invention, taken in connection with the accompanying sheets of drawings, forms a full, clear, and exact specification, which will enable others skilled in the art to which our said invention appertains to make and use the same.

This invention has general reference to pipe bending and pipe coiling machines; and it consists, essentially, in the novel and peculiar combination of parts, and details of construction, as hereinafter first fully set forth and described, and then pointed out in the claims.

The object of this invention is the production of a power-operated machine for efficiently, accurately, and rapidly bending and coiling pipes and rods. It is especially adapted for operation on cold pipe up to three inches in diameter, but may also be made to take and bend larger sized pipes.

In the accompanying drawings which illustrate the preferred embodiment of our invention, Figure 1 is a side elevation of one form of our pipe bending machine. Fig. 2 is a perspective view of one style of links employed in this machine; and Fig. 3 is a like view of another style of links employed therein. Fig. 4 is a rear elevation of the machine. Fig. 5 is a plan of the machine drawn on an increased scale, part of the gearing employed to rotate the upper forming roll being omitted. Fig. 6 is an end view of a detail of construction and illustrating means for spacing or pitching the convolutions of a coil of pipe. Fig. 7 is an end elevation of the machine. Fig. 8 is a sectional elevation of a part of the machine, on line 11—11 of Fig. 7. Fig. 9 is a view of the gearing employed by which the three forming rolls used in this machine are rotated.

Like parts are designated by the same characters and symbols of reference in all the figures.

This machine includes a pair of parallel, spaced-apart housings A, A^a, preferably mounted on a base or bed plate B, which latter plate is suitably supported on legs C.

These housings are, preferably, plates of proper thickness, edged on three margins by ribs or flanges 12, to impart rigidity and stiffness to these plates. In each of these plates there is medially, an excision 13, best shown in Fig. 2, which excisions extend from the upper margins of the plates downwardly for some distance, and in which excisions are mounted boxes or journals for the upper forming-roll shaft, to which specific reference will be hereinafter had.

From the upper margin of the plate A, and at one end thereof, extends substantially horizontally, a bracket 14, terminating in a bearing 15, in which there is rotatably mounted a driving shaft 16, carrying at its outer end means for imparting rotative movement to said shaft 16, such as tight-and-loose pulleys 17, 18, said shaft 16 having at its opposite end a worm 19, which engages a worm wheel 20, fixed to a shaft 21, which may traverse the space between the housings A, A^a, as indicated in Fig. 1, and may be journaled in bearings 22, 22^a, 75 or may have only a short shaft 21, and a single bearing 22, as illustrated in Fig. 5. Adjacent the worm wheel 20 there is mounted on shaft 21 a gear pinion 23, which meshes with a spur gear wheel 24, mounted on a 80 shaft 25, which shaft traverses the space between the housings A, A^a, and carries at its outer end the first one of a set of three forming rolls 26, 27, and 28. This shaft is journaled in bearings 29, 30, Fig. 5, secured 85 to the housings A, A^a. The second forming roll 27 is mounted on a shaft 31, journaled in bearings 32, 33, secured to the housing A, A^a, while the third forming roll 28 is mounted at the end of a shaft 34, having its bearings 35, 36, in an inverted U-shaped yoke D, best shown in Fig. 8. The two roller shafts 31 and 34 are rotated by mechanism best illustrated in Fig. 9, and comprises a gear wheel E, mounted on the first roller shaft 100 25, a second gear wheel F, mounted on the second roller shaft 31, and an intermediate gear pinion G, the latter gear pinion being mounted on a shaft 37, journaled in bearings 38, fixed to the housings A, A^a. Upon 105 the third roller shaft 34 there is fixed a gear wheel H; but since this shaft with its gear wheel H and forming roll 28 is designed for vertical movement, and since the forming roll 28 must, of necessity, rotate in 110 a direction opposed to that of the forming rolls 26 and 27, this gear wheel H is con-

ected to the gear wheel E on the first roller shaft by two gear pinions I, J, mounted on shafts 39, 40, which shafts rotate in bearings in the following manner:

- 5 Upon the first roller shaft 25 and the third roller shaft 34 there are mounted links G, shown in detail in Fig. 2, and comprising each a tubular hub 41, which hubs engage the shafts 25 and 34, and two 10 punctured eyes 42, engaging the shafts 40 and 39, a web 43 connecting the hub 41 and eyes 42. Connecting the shafts 39 and 40, there is a link L, shown in detail in Fig. 3, and comprising two eye-members 44, 45, 15 connected by a plate 46, the eyes 44, 45, engaging the spaces 47 between the eyes 42 of the links K.

By means of these links the gear wheel H may move vertically and still remain in 20 perfect mesh with the intermediate pinion J, the latter pinion in proper engagement with the pinion L, and this pinion, in turn, with the driving gear wheel E.

The U-shaped yoke D is vertically moved 25 by mechanism including the following elements:

Upon each of the horizontally disposed ribs or flanges 12 of the housing plates there is bolted by bolts 48, Figs. 4 and 5, 30 an inverted, U-shaped member M, the space between the parallel members of which forms a continuation of the excisions 13 in the plates A, A^a, and thus forms guide ways for the bearings on the yoke D, there 35 being in the connecting bar 50, of the members D, and medially thereof, a screw-threaded opening 51, wherewith engages an adjusting screw 52, which rotates in a bearing 53, formed in a cross bar 54, connecting the two members M, and bolted 40 thereto by screws 55. Upon the upper end of this screw 52 there is affixed an element 56, by which the screw 52 may be rotated. This element may be a hand wheel, in a 45 machine in which only helical coils of pipe will be formed; but in a machine wherein also spirals are to be formed, this element 56 will be a worm wheel, and this worm wheel is then rotated by gearing comprising 50 the following instrumentalities:

Extending from the members M there are brackets 57, shown best in Fig. 7, having bearings 58, in which is rotatably mounted a shaft 59, carrying a worm 60, 55 engaging the worm wheel 56. This shaft 59 has at one end a hand crank 61, by which it may be rotated to make primary adjustment of the screw 52; but when this screw is to be automatically rotated we employ 60 gearing comprising a gear wheel 62, removably secured to that end of the shaft 59 opposed to the end carrying the hand crank 61. As shown in Fig. 1, there are on the brackets 57 further bearings 63, in 65 which rotates a shaft 64, carrying at one

end a gear wheel 65, meshing with the gear wheel 62; and in one embodiment of our invention, as shown in Figs. 1, 4 and 7, there is on the shaft 64 behind the gear wheel 65 a further gear wheel 66, which engages the 70 large spur wheel 24, and thereby rotates shaft 64. These gear wheels 62 and 65 are removably placed upon their shafts and constitute so-called change gears, that is to say, they may be changed for others of different diameters, as long as they are so planned that their centers are of the same distance axially. By changing these gears we can attain any desired rotative speed of the lifting screw 52, and thereby vary 80 the diameter of the convolutions of a spirally coiled pipe, as the spiral is being developed.

In Figs. 1 and 4, we have shown the gear wheels 65 and 66 of the same diameter, and the driven gear wheel 62 proportionately reduced, while in Fig. 5 we show the gear wheel 65 of smaller, and the gear wheel 66 of proportionately larger diameter to illustrate this point of employing change 90 gears for rotating the screw 52.

For the purpose of properly spacing the convolutions of a coil of pipe any desired distance apart, we employ the device shown in Figs. 1, 5 and 6, comprising a bar 80, 95 preferably of semicircular cross section. This bar is placed on that side of the top forming roll from which the pipe which is being bent will issue and thereby pass the bar 80 and be slightly deflected. This bar has a shank 81, which is acted upon by a set screw 82, to keep the pipe deflect-bar 80 in adjusted position and thereby determine the pitch of the pipe coil by a horizontal movement of the bar 80 in an obvious manner. As a modification of this pipe deflecting device we may mention that, as illustrated in Fig. 5, a curved washer 83, placed in front of the upper forming roll, will act in a more or less satisfactory manner as a spacer for the coil-convolutions, which curved washer 83 may be backed up by one or more washers 84, indicated in dotted lines in Fig. 5, to vary 100 the pitch of the coil-convolutions. This 105 curved washer 83 functions in the following manner: When the pipe to be coiled passes the three forming rolls and leaves the forming roll 27 and has made approximately a complete turn, it passes in front 110 of the curved washer 83 and is thereby deflected from its straight course, the degree of deflection being determined by the distance from the center of the groove in the forming roll 28 and the flank of the curved 115 washer, the flank of the washer being convex in order to guide the advancing end of the pipe in front of this washer.

We have heretofore described the machine as being provided with but one each 120

of the gear wheels G, E, I, J, and H; but in practice we prefer to employ two of each of these gear wheels, which are placed in pairs on their respective shafts, as illustrated 5 in Fig. 7, to better to distribute and equalize the strain or stress on these shafts, and to provide for a more secure operation of the machine.

The operation of this machine will be 10 readily understood from the foregoing description, and may be briefly summarized, as follows:

When helical coils are to be formed in which all the convolutions are of the same 15 diameter, the screw-rotating device is disconnected from the large spur gear wheel by removing one of the change gears, or by placing the trundle gear in normal position, which permits the shaft 59 on which the 20 worm 60 is mounted being rotated by the hand crank 61 to make proper adjustment of the upper forming roll for diameter, and then moving the pipe deflecting element 80 for pitch of the coil. When, however, conical 25 spiral coils are to be formed, a proper set of change gears is placed on their shafts and the machine set for the smallest diameter of the spiral. Then the screw-rotating mechanism is placed in operation when the 30 following convolutions will be formed with progressively larger diameters until the coil is completed. The coil thus formed will be, of necessity a truncated cone of the desired pitch; but if the coils are desired to be all 35 the same plane, it will be necessary to support the coil at its outermost convolution and depress the center until all the convolutions are in the same plane.

The relative sizes of the change gears may 40 have to be determined by actual experiments and will depend upon the size of the coil, the size and thickness of the pipe, its material, and its hardness, so that a fixed standard of change gears cannot well be determined in advance of actual trial, but when once ascertained can be readily duplicated later on.

We have hereinbefore described with considerable minuteness the preferred embodiment of our invention, but we desire it to be understood that we are aware that many of the details disclosed may be changed, and parts omitted without departing from the scope of our invention as defined in the 55 subjoined claims.

Having thus fully described our invention, we claim as new and desire to secure by Letters Patent of the United States—

1. In a pipe bending and coiling machine, 60 the combination, of a pair of housings in parallel spaced relationship, said housings having approximately medially slotted openings, a pair of shafts in said housings in parallel spaced relationship, fixed bearings in said housings for said pair of shafts, 65 a grooved forming roll at one end of each of said pair of shafts, means for operatively connecting the pair of shafts, a U-shaped element upon each of said housings, the spaces between the parallel members of said 70 elements being alined with the slots in said housings, a yoke, said yoke having bearings engaging said slots, a shaft in the latter bearings, a grooved forming roll at the end of the last-mentioned shaft and alined 75 with the other forming rolls, gearing connecting the first forming roll shaft to the second forming roll shaft, and other gearing connecting the first forming roll shaft to the third forming roll shaft. 80

2. In a pipe bending and coiling machine, the combination, of a pair of housings in parallel spaced relationship, said housings having approximately medially slotted openings, a pair of shafts in said housings in parallel spaced relationship, fixed bearings in said housings for said pair of shafts, 85 a grooved forming roll at one end of each of said pair of shafts, means for operatively connecting the pair of shafts, a U-shaped 90 element upon each of said housings, the space between the parallel members of said elements being alined with the slots in said housings, a yoke, said yoke having bearings engaging said slots, a shaft in the 95 latter bearings, a grooved forming roll at the end of the last-mentioned shaft and alined with the other forming rolls, gearing connecting the first forming roll shaft to the second forming roll shaft, other gearing connecting the first forming roll shaft to the third forming roll shaft, and means for raising and lowering said yoke. 100

3. In a pipe bending and coiling machine, the combination, of a pair of housings in 105 parallel spaced relationship, said housings having approximately medially slotted openings, a pair of shafts in said housings in parallel spaced relationship, fixed bearings in said housings for said pair of shafts, 110 a grooved forming roll at one end of each of said pair of shafts, means for operatively connecting the pair of shafts, a U-shaped element upon each of said housings, the space between the parallel members of said 115 elements being alined with the slots in said housings, a yoke, said yoke having bearings engaging said slots, a shaft in the latter bearings, a grooved forming roll at the end of the last-mentioned shaft and alined with 120 the other forming rolls, means for operating one of said forming roll shafts, gearing for connecting the third forming roll shaft to the first forming roll shaft, and means for automatically raising and lowering said 125 yoke.

4. In a pipe bending and coiling machine, the combination, of a pair of housings in parallel spaced relationship, said housings having approximately medially slotted 130

- openings, a pair of shafts in said housings in parallel spaced relationship, said shafts being horizontally mounted in said housings, fixed bearings in said housings for said 5 pair of shafts, a grooved forming roll at one end of each of said pair of shafts, means for rotating one of this pair of shafts, said means including a shaft, a worm on said shaft, a worm wheel, a gear pinion in the 10 rear of and adjacent to said worm wheel, a shaft upon which the worm wheel and the gear pinion are rotatively mounted and a large spur gear wheel mounted upon the one of the pair of shafts and meshing with said 15 gear pinion, a third forming roll shaft in said housing intermediate of and above the pair of forming rolls, a grooved forming roll at the end of said third forming roll shaft and alined with the other forming 20 rolls, means connecting the first forming roll shaft to the second forming roll shaft, other means for connecting the first forming roll shaft to the third forming roll shaft, a yoke in which the third forming roll shaft is rotatably mounted, and means for raising and 25 lowering said yoke, said means being connected to the first forming roll driving mechanism.
5. In a pipe bending and coil forming 30 machine, the combination, of a pair of housings in parallel spaced relationship, said housings having approximately medially slotted openings, a pair of spaced apart bearings in horizontal alinement in said 35 housing, a shaft rotatably mounted in each of said pairs of bearings, a grooved forming roll at the outer end of each of said shafts, an inverted U-shaped yoke, said yoke having journal bearings at the terminals of the par- 40 allel members of said yoke, said yoke being vertically movable in said openings, a shaft rotatably mounted in the latter bearings, a grooved forming roll at the end of the latter shaft and alined with the two first-named 45 forming rolls, gearing for imparting rotative movement to the first forming roll shaft, gearing for imparting rotative movement to the second forming roll shaft from the first forming roll shaft, other gearing for im- 50 parting rotative movement to the third forming roll shaft from said first forming roll shaft, the latter gearing including a gear wheel fixed to the first forming roll shaft, a further gear wheel fixed to the third
- forming roll shaft, and a pair of intermediate gear wheels, said pair of intermediate gear wheels being in mesh with each other, one of said intermediate gear wheels being in mesh with the gear wheel on the first forming roll shaft, the other of said 60 intermediate gear wheels being in mesh with the gear wheel on the third forming roll shaft, a shaft for each of said intermediate gear wheels, a link connecting the first forming roll shaft to the shaft carrying the first 65 intermediate gear wheel, a further link connecting the third forming roll shaft to the shaft of the second intermediate gear wheel shaft, and a third link connecting the two intermediate gear shafts, and means for man- 70 ually, and automatically raising and lowering the yoke carrying the third forming roll shaft, said latter means being connected to the first forming roll driving mechanism and including removable change-gear mechanism 75 for varying the speed of the vertical movement of said yoke.
6. In a pipe bending and coil forming machine, the combination, of a set of three grooved forming rolls in spaced relationship, two of said forming rolls being rotatively arranged in fixed bearings, an inverted U-shaped yoke, the free ends of said yoke being formed into bearings, a shaft rotatably mounted in said bearings, a third 80 forming roll on the latter shaft, the third forming roll being constructed to move vertically with said yoke, means for rotating said forming rolls including a main spur gear wheel, and means for raising and lower- 85 ing said third forming roll, said means including screw mechanism connected with the said yoke, and mechanism for automatically 90 rotating said screw mechanism while said forming rolls are rotating, said latter mech- 95 anism including a driven gear wheel in mesh with said main spur gear wheel, a set of interchangeable gear wheels of varying diameters a pair of which is rotatably connected to the said driven gear wheel and 100 operatively connected to said screw mechanism.
- In testimony that we claim the foregoing as our invention, we have hereunto set our hands at Chicago, Cook county, State of Illinois, this 5th day of February, 1918.
- BERNHARDT SCHENK.
JOSEPH SZOKE.
